UNITED STATES PATENT OFFICE.

JOHN A. MILNER, OF WHITE BEAR LAKE, MINNESOTA.

CAR-DOOR LOCK.

1,249,168.

Specification of Letters Patent.

Patented Dec. 4, 1917.

Application filed March 8, 1917. Serial No. 153,302.

To all whom it may concern:

Be it known that I, JOHN A. MILNER, a citizen of the United States, residing at White Bear Lake, in the county of Ramsey 5 and State of Minnesota, have invented a new and useful Improvement in Car-Door Locks, of which the following is a specification.

This invention relates to that class of car door locks, which is particularly adapted 10 for use in locking freight car doors against intrusion by unauthorized persons. The pil- lage of freight cars has become a serious loss to railroads due to the means now em- ployed being ineffective, and it is the pri- 15 mary object of this invention to overcome this objection in a simple, inexpensive and efficient manner.

With this and other objects in view my invention comprises the features of con- 20 struction and combination of parts herein- after particularly described and set forth in the claims.

In the accompanying drawing forming part of this specification, Figure 1 is a side 25 elevation of a detail of a freight car looking at one of the inner side walls and door showing my improved lock applied thereto; Fig. 2 is another view similar to that illustrated in Fig. 1 illustrating the position of the 30 parts of my improved lock when the parts assume fully locked position; Fig. 3 is an enlarged sectional view of a detail taken on the line X—X of Fig. 1; Fig. 4 is an- other section of a detail taken on the line 35 Y—Y of Fig. 1; and Fig. 5 is a side elevation of a train of cars illustrating the air line system of usual construction with which my invention coöperates.

In the drawing, let A indicate a detail of 40 a freight car of usual type, my invention being adapted for use on any character of car desired with sliding or swinging door or doors. B indicates one of the doors of the car which as illustrated is of sliding type 45 and adapted to close the usual doorway 2 in one of the sides 3. This door is adapted to be locked in closed position by means of a catch or latch 4 carried by the door on the inside of the car and a lock bolt 5 which 50 is carried by the door jamb or frame of the doorway, also on the inside of the car. The catch 4 is in the form of a pawl, the body of which is pivotally mounted by means of the pin 6 on the fixture 7, which is secured 55 to the inner face of the door B near the edge portion 8 by means of bolts 9 or other suit-

able fastening means. The outer extremity of said pawl is formed with a shoulder 10 and a guiding inclined face 11 on its outer end. The lock bolt or keeper 5 is held in 60 a keeper fixture 12, which is secured by bolts 13 or other suitable fastening means to the inner face of the door frame or wall of the car and is formed with superimposed keeper arms 14 having bolt receiving openings 15 65 through which the lock bolt 5 is passed downwardly. The lock bolt is formed with an upper shoulder 16 and eye piece 17, said shoulder being adapted to rest on the upper keeper member 14 to prevent the bolt from 70 dropping through the openings in the keeper. A short chain 18 secured to the wall of the car and to the eye piece 17 serves to prevent the lock bolt from being lost when it is lifted out of the keeper. A leaf spring 75 19 is carried by the keeper and is so situated as to press and maintain the pawl 4 with its shoulder 10 engaged with the lock bolt 5 when the door B reaches fully closed position. 80

Thus when it is desired to lock the door closed, the bolt 5 is placed in position through the openings 15 in the keeper fixture and the pawl is made to engage by its shoulder 10, said bolt when the door reaches 85 fully closed position. The lock being situated on the inside of the car makes it impos- sible for the door to be opened from the outside when locked, except by mutilation. The part of the apparatus described is 90 adapted for use when a car has been loaded and is standing upon the tracks ready to be coupled to a train for a journey, and once it has been closed and locked, it is impossible to open the same until the lock bolt 5 has 95 been ejected from the keeper fixture.

Arranged in connection with modern freight cars is the usual air pressure line which is maintained under air pressure by an air pressure supply mechanism carried 100 by the locomotive for operating brakes and other parts of the train operating mechanism. Each car is provided with part of said air line such as 20, which line may be connected with an auxiliary air chamber 21 105 constituting part of the pipe line system. To this chamber I have connected an air pressure supply duct 22 leading up into the car alongside of the door way to a lock bolt actuator E, which is preferably arranged 110 immediately below the keeper 12. This ac- tuator is in the form of a cylinder 23 se-

cured to the side of the car and containing a plunger piston 24, which carries a shaft 25 co-axially arranged in the cylinder and projecting through an opening 26 in its upper end, immediately below the lower end of the lock bolt 5. The air pressure supply duct 22 is connected with the lower end of the cylinder 23 immediately below the piston 24 and upon the admission of air under pressure by the pipe system, the piston is forced upwardly carrying with it the plunger shaft 25, which acts as an ejector to force the lock bolt 5 upwardly out of the keeper and assume its position as a lock pin 10 in the keeper behind the shoulder 10 of the catch 4. Thus when the cars are coupled to the locomotive as illustrated in Fig. 5 and the train air line system maintained under pressure by the air pressure mechanism F 15 on the locomotive, the pressure of air in the air line causes all of the actuators E in the cars of the train to eject the lock bolts such as 5 out of their keepers, and simultaneously lock the doors B closed by the members 25 20 passing upwardly through the openings 15 in the keepers 12 and engage and hold the lock members 4 locked until pressure of air is released from the train line either by opening the air line or by shutting off the pressure of air in the locomotive purposely. 25 Should any one of the ducts 22 in the cars be broken by an intruder, a signal such as a whistle 27 on the tank 21 will immediately indicate by sound the location of the car 30 into which an attempt is being made to enter. As soon as the air pressure in the air line is released either purposely or otherwise, the piston 24 will return by gravity in the cylinder 23 to normal position in the lower end of the air cylinder 23, whereupon the ejector pin 25 will release the catch 4 35 and leave the door B free to be opened from the outside. The spring 19 holds at all times the catch 4 in engagement either with the lock bolt 5 or the ejector shaft 25, whichever happens to be in position in the keeper, provided the door B has been closed.

The device described is very simple in construction and effective in operation, preventing at all times when the train of cars is in transit, an intruder entering any of the cars without sounding a signal or affecting the operation of the train, it being obvious that if any one of the air supply ducts 50 22 is broken or an opening in the air pressure system made for the escape of air, the engineer in the cab of the locomotive or the conductor will immediately know from the operation of the usual indicator in train line system that some trouble exists.

The air pressure tank 21 it will be understood represents what is generally termed one of the "auxiliary air chambers" for operating "brake mechanism," "signal mechanism" or any other part of the air operated

mechanism of the car or train, and that the duct 22 may be connected to one of the air reservoirs or any part of the air line system desired. It will be further understood that the part indicated above as the signal whistle 70 27 may be inclosed in a protecting guard such as 29, to insure against malicious destruction of same.

In accordance with the patent statutes I have described the principles of operation of my invention, together with the apparatus which I now consider to represent the best embodiment thereof, but I desire to have it understood that the construction shown is only illustrative, and that the invention can 75 be carried out by other means and applied to uses other than those above set forth within the scope of the following claims.

Having described my invention, what I claim as new and desire to protect by Letters Patent is:—

1. In combination with a doorway and a door therefor, a latch and removable keeper for locking said door closed and a pneumatically actuated keeper arranged to eject and assume the function of said removable keeper.

2. In combination with a car having a door and an air line, a latch and keeper for locking said door closed and means operated by the pressure of air in said line for assuming the place of said keeper to maintain said latch locked and releasing said latch when the pressure of air in said line is reduced or released.

3. In combination with a car having a door and an air line, means for locking said door closed having a keeper, and means operated by the force of air in said line for assuming the place of said keeper to maintain said latch locked and removable to unlock 105 said latch when pressure of air in said line is reduced or released.

4. In combination with a car having a door-way and a door therefor, a latch and removable keeper for locking said door closed 110 and a pneumatically actuated keeper arranged to eject and assume the function of said removable keeper, said parts being completely isolated from the exterior of the car.

5. In combination with a car having a door, a lock for said door accessible only from inside said car and having a keeper and a removable lock bolt arranged to mechanically hold said door closed, an air pressure 120 line carried by said car, and means connected with said line leading into said car having an ejector shaft for forcing said bolt out of said keeper and maintaining said lock in locked condition under the pressure of air 125 from said line, said shaft automatically receding into unlocked position when air in said line is released.

6. In combination with a car having a door and an air pressure line, a lock in said 130

car having a removable bolt for holding said door closed, a cylinder connected with said line, a piston carrying an ejector shaft for replacing said bolt in said lock and holding 5 said door closed under the pressure of air from said line and receivable into unlocked position when the air pressure of said line is

released, and a signal carried by said car in said line adapted to remain dormant when air pressure is maintained in said line but to 10 become active should air pressure be released.

In testimony whereof, I have signed my name to this specification.

JOHN A. MILNER.
